LEVEL DETERMINING DEVICE

Mitchell Bobrick, Pacific Palisades, Calif., assignor to
Mitchell Bobrick, Inc., Beverly Hills, Calif., a corpora-
tion of California

Filed Jan. 16, 1968, Ser. No. 10,181

Term of patent 14 years

(Cl. D52—6)

FIG. 1.

FIG. 2.

FIG. 3.

FIG. 4.

FIG. 5.

FIG. 1 is a perspective view of the level determining device;

FIG. 2 is an end view, the ends being identical;

FIG. 3 is a top plan view;

FIG. 4 is a bottom plan view; and

FIG. 5 is a side elevational view, the sides being identical, said view illustrating for illustrative purposes a service extension bar in phantom lines removably installed in the device.

I claim:

The ornamental design for a level determining device, as shown and described.
